APPARATUS FOR HEATING FLUIDS

William C. Seifert, Narberth, Pa., assignor to Electric Heating Equipment Company, Philadelphia, Pa., a corporation of Delaware

Application April 15, 1941, Serial No. 388,642

10 Claims. (Cl. 122—333)

Many chemical reactions must, for maximum efficiency, be conducted under closely controlled temperature conditions. Heating of the reacting materials may be effected by circulating a heated fluid in indirect heating relationship to the reacting materials or by conducting a vapor into indirect heating relationship thereto. In order to obtain close control of the reaction temperature the temperature of the heating liquid or the pressure of the heating vapor should be exactly maintained. In practice this presents difficulties owing to variations in the heating load as the result of various factors and a lag in the response to such variations of the apparatus in which the heating liquid is heated or the heating vapor is produced. The apparatus of my invention is adapted either to heating a liquid or to heating and vaporizing a liquid. It is adapted, inter alia, to supply a heated liquid to be used to heat indirectly materials undergoing chemical reaction or physical alteration. It is also adapted to heat and vaporize a liquid to produce a vapor to be similarly used. In either case the response to variations in the applied load is so rapid and complete that the liquid is supplied at a substantially constant temperature or the vapor at a substantially constant temperature and pressure.

The invention will be fully understood from the following description read in conjunction with the drawings in which—

Fig. 1 is a longitudinal vertical section through the apparatus of my invention (a few parts appear in side elevation and not in section);

Fig. 2 is a transverse vertical section through the apparatus shown in Fig. 1;

Fig. 3 is a schematic diagram of the apparatus shown in Figs. 1 and 2; and

Fig. 4 is a detail of part of Fig. 3.

Fig. 5 is a detail of part of Fig. 3; and

Fig. 6 is a detail of an alternative form of part of the construction shown in Fig. 3.

Referring to Figs. 1 and 2, the apparatus includes a receptacle in which fluid is heated or heated and vaporized. In the specific embodiment herein described this receptacle 1 includes upper drum 2, communicating through duct 3 with intermediate drum 4 which in turn is connected by circulatory tubing 5 with lower drum 6. Tubing 5 (Fig. 2) is bent to define a cylinder 7 into which combustion products are discharged from burner 8 (Fig. 1). Muffle 10 is interposed between the combustion products and the tubing. At the muffle outlet 11 these combustion products which have there become reduced in temperature and more uniform in composition are discharged and circulate around the tubing and in contact with the lower part of drum 4 passing off through stack 12. Upper drum 2 carries a number of immersion type heaters 13, 14, 15, 16 and 17. These consist of an electric

resistance element carried in a tubular covering from which the resistance element is electrically insulated. Drum 2 is also provided with outlet 18. Drums 4 and 6 and the connecting tubing 5 are in refractory setting 26. Drum 4 rests on this setting while drum 2 is supported by I-beams 27 and 28 which rest indirectly on the setting.

If the apparatus is operated to heat fluid, i. e., to heat and deliver unvaporized fluid in liquid phase, the fluid is introduced through inlet 20 and forced by pump 21 driven by motor 22 through pipe 23 into lower drum 6. Valve 24 may be closed or may be partly open to provide additional circulation between drums 4 and 6 moving downwardly through pipe 25 horizontally through pipe 23 into drum 6, thence upwardly through tubing 5 into drum 4, absorbing heat from burner 8 in passage. From drum 4 it moves through duct 3 into drum 2 in which it absorbs heat from electric heaters 13-17. The heated liquid leaves the apparatus through outlet 18. If, conversely, the apparatus is used to heat and vaporize fluid, i. e., to generate and deliver a heating vapor, the condensate is returned to the apparatus through inlet 20. Valve 24 is fully opened and pump 21 is operated to maintain rapid circulation from drum 4 downwardly through pipe 25 horizontally through pipe 23 into drum 6 upwardly through tubing 5 into drum 4 absorbing heat from burner 8 in its passage. From drum 4 it moves through duct 3 into drum 2 in which it absorbs heat from electric heaters 13-17. The amount of liquid in the system is in this case sufficient to cover these heaters, but insufficient to fill drum 2, leaving a vapor space above the liquid while the vapor produced moves out of the apparatus through outlet 18.

The mode of control of the heating or heating and vaporization will be evident from the diagrammatic showing in Figs. 3 and 4. Burner 8 is supplied with oil or other fuel at a constant pressure by pressure reduction valve 30. It receives air through inlet 31. The amount of fuel and air supplied to the burner and consequently the amount of heat delivered by the burner is regulable by burner control lever 32. This lever is connected through push rod 33 with lever 34 of electric control 35. Lever 34 is pivotally mounted at 36. The upper end of lever 34 carries a strong electromagnet 37 suitably energized. The manner by which the position of lever 34 (and, consequent adjustment of burner control) is determined will be hereinafter described.

With respect to the electric heater 13-17, one leg of each of these is connected to lead 41. The other leg of heater 13 is carried to contact 13' of heater 14 to contact 14', etc. The number of heaters in circuit between leads 41 and 42 is determined by wiping contactor bar 43 carried by lever 44 pivotally mounted at 45. Lever 44 car-

ries strong electromagnet 45'. The manner by which the position of lever 44 (and consequent number of heaters in operation) is determined will be hereinafter described.

If the apparatus is used to heat fluid, meter 51 (Fig. 3) is responsive to temperature preferably the temperature of the heated fluid adjacent outlet 18. In Fig. 5 I have shown a form of control adapted to this purpose. In this case the meter 51 is assumed to be responsive to slight variations in E. M. F. induced in a thermocouple surrounded by the fluid which is heated and for this purpose the conducting leads 101 and 102 are carried from the meter 51 to a thermocouple 103 formed of the dissimilar metals 104 and 105, which thermocouple is located in the well 106 located immediately in the path of the liquid moving upwardly through pipe 18. If the apparatus is used to heat and vaporize fluid, the meter 51 may be responsive to temperature but is preferably responsive to the parallel function vapor pressure. In this case the vapor pressure is carried to the instrument from adjacent outlet 18 through pipe 52. A section through outlet 18 and pipe 52 is shown in Fig. 6. Meter 51 is provided with indicating needle 53 which, with increase in temperature or pressure, moves toward the right. The scale 54 includes the predetermined temperature or pressure to be maintained and a range above (right) and below (left). The needle 53 (Fig. 4) is mounted on a wiping contact 55 which in the horizontal movement makes wiping contact with any one of five stationary contacts 61, 62, 63, 64 and 65 or with any one of five stationary contacts 71, 72, 73, 74 and 75. Wiping contact 55 is connected to lead 66. Stationary contacts 61-5 inc. are mounted on an insulating backing and may be moved horizontally as a unit by a worm controlled by hand wheel 67. Stationary contacts 71-5 inc. are mounted on an insulating backing and may similarly be moved horizontally as a unit by a worm controlled by hand wheel 77. Separate control is provided so that one unit may, if desired, be set slightly in advance of the other, but in general contacts 61-65 inc. will be exactly above contacts 71-75 inc. Contacts 61-65 inc. are connected through leads 61', 62', 63', 64' and 65' to relays 61'', 62'', 63'', 64'' and 65'', the primaries of which are in turn connected to lead 66'. This is necessary since only currents of low potential and intensity can be handled by the wiping contact 55. The secondaries of the relays are connected to lead 68 which is a source of higher potential and intensity and the relays control respectively secondary circuits 81, 82, 83, 84 and 85 connected respectively to field magnets 81', 82', 83', 84' and 85'. These are in turn connected to lead 68'. It is evident from the foregoing that the position of lever 34 and consequent burner adjustment is determined by the relative position of indicating needle 53. In practice the contacts 61-65 inc. are set so that the central contact 63 will register with needle 53 and wiping contact 55 when the needle is in the center of the permissive range of temperature or pressure to be maintained or when the needle is at the exact temperature or pressure to be maintained. A movement of the needle to the right and therefore to a higher reading results in a shift of the burner to an adjustment of lower heat input and conversely.

Contacts 71, 72, 73, 74 and 75 are connected through leads 71', 72', 73', 74' and 75' to relays 71'', 72'', 73'', 74'' and 75'', the primaries of

which are in turn connected to lead 66'. The secondaries of the relays are connected to lead 68 and the relays control respectively secondary circuits 91, 92, 93, 94 and 95 connected respectively to field magnets 91', 92', 93', 94' and 95'. It is evident from the foregoing that the position of lever 44 and consequently the number of electric heaters in operation is determined by the relative position of needle 53.

In operation, therefore, when needle 53 moves to the right from the predetermined point as the result of an increase in pressure or temperature, both burner and electric heater move automatically to a position of lower heat input. Assuming, for example, that the needle moves to the right and wiping contact 55 moves to stationary contacts 65 and 75, an immediate and substantial reduction in heat input results from putting electric heaters 15 and 16 out of operation. The response of the burner is slower and as soon as this becomes effective the needle will move toward the temperature or pressure to be maintained and wiping contact 55 will move to points 64 and 74. Whenever the heating load returns to normal the needle will return to its original position and wiping contact 55 to contacts 63 and 73.

Conversely, when needle 53 moves to the left as the result of a decrease in pressure or temperature, both burner and electric heater move automatically to a position of higher heat input. Assuming, for example, that the needle moves to the left and wiping contact 55 moves to stationary contacts 61 and 71, an immediate and substantial increase in heat input results from putting electric heaters 13 and 14 in operation. The response of the burner 8 is slower and as soon as it becomes effective the wiping contact 55 moves to points 62 and 72. Whenever the heating load returns to normal the needle will return to its original position and wiping contact 55 to contacts 63 and 73.

In general the proportionality between electric heat input and non-electric heat input (neglecting lag) is substantially maintained throughout the entire working range and preferably from 60-85% of the total heat input is non-electric while from 15-40% is electric. If, however, the variations in load are relatively small, the proportion of electric to non-electric heat input may also be reduced, it being only necessary that the electric heating elements have a capacity sufficient to enable them to respond immediately to variations in the heating load, thereby neutralizing the inevitable lag in effectiveness of the non-electric heating means.

Examples of liquids that may be heated or heated and vaporized in my apparatus are water, oil, diphenyl, diphenyl-oxide and mercury.

The foregoing description is by way of illustration and not of limitation, and it is, therefore, my intention that the invention be limited only by the appended claims or their equivalents, in which I have endeavored to claim broadly all inherent novelty.

I claim:

1. Apparatus for continuously heating fluid to a predetermined temperature comprising a receptacle subdivided into an upper and at least one lower drum connected thereto, means for indirectly heating by combustion fluid in said lower drum, means for varying the amount of heat supplied by said heater, an electric resistance heater in said upper drum, means for varying the amount of heat supplied by said resistance heater, means

responsive to temperature of fluid in said receptacle controlling both said means for varying adapted to vary both said means simultaneously.

2. Apparatus for continuously heating fluid to a predetermined temperature comprising a receptacle subdivided into an upper and at least one lower drum connected thereto, means for indirectly heating by combustion fluid in said lower drum, means for varying the amount of heat supplied by said heating means, an electric resistance heater in said upper drum, means for varying the amount of heat supplied by said resistance heater, means responsive to temperature of fluid in said receptacle controlling both said means for varying adapted to vary both said means simultaneously at a rate such that the proportionality between the heat supplied by said first mentioned heater and the heat supplied by said resistance heater is substantially constant throughout the working range.

3. Apparatus for continuously heating fluid to a predetermined temperature comprising a receptacle subdivided into an upper and at least one lower drum connected thereto, circulatory tubing communicating with said lower drum, a fuel burner in heating relationship to said tubing, means for varying the amount of heat supplied by said fuel burner, an electric resistance heater in said upper drum, means for varying the amount of heat supplied by said resistance heater, means responsive to temperature of fluid in said receptacle controlling both said means for varying adapted to vary both said means simultaneously.

4. Apparatus for continuously heating fluid to a predetermined temperature comprising a receptacle subdivided into an upper and at least one lower drum connected thereto, circulatory tubing communicating with said lower drum, a fuel burner in heating relationship to said tubing, means for varying the amount of heat supplied by said fuel burner, an electric resistance heater in said upper drum, means for varying the amount of heat supplied by said resistance heater, means responsive to temperature of fluid in said receptacle controlling both said means for varying adapted to vary both said means simultaneously at a rate such that the proportionality between the heat supplied by said fuel burner and the heat supplied by said resistance heater is substantially constant throughout the working range.

5. Apparatus for continuously heating fluid to a predetermined temperature comprising a receptacle subdivided into an upper and at least one lower drum connected thereto, circulatory tubing communicating with said lower drum, a fuel burner in heating relationship to said tubing, a muffle between said burner and said tubing, means for varying the amount of heat supplied by said burner, an electric resistance heater in said receptacle, means for varying the amount of heat supplied by said resistance heater, and means responsive to temperature of fluid in said receptacle controlling both said means for varying adapted to vary both said means simultaneously.

6. Apparatus for continuously heating and vaporizing fluid at a predetermined temperature comprising a receptacle sub-divided into an upper and at least one lower drum connected thereto, means for indirectly heating by combustion fluid in said lower drum, means for varying the amount of heat supplied by said heating means,

an electric resistance heater in said upper drum, means for varying the amount of heat supplied by said resistance heater, means responsive to vapor pressure in said receptacle controlling both said means for varying adapted to vary both said means simultaneously.

7. Apparatus for continuously heating and vaporizing fluid at a predetermined temperature comprising a receptacle sub-divided into an upper and at least one lower drum connected thereto, means for indirectly heating by combustion fluid in said lower drum, means for varying the amount of heat supplied by said heating means, an electric resistance heater in said upper drum, means for varying the amount of heat supplied by said resistance heater, means responsive to vapor pressure in said receptacle controlling both said means for varying adapted to vary both said means simultaneously at a rate such that the proportionality between the heat supplied by said first mentioned heating means and the heat supplied by said resistance heater is substantially constant throughout the working range.

8. Apparatus for continuously heating and vaporizing fluid at a predetermined temperature comprising a receptacle sub-divided into an upper drum and at least one lower drum connected thereto, circulatory tubing communicating with said lower drum, a fuel burner in heating relationship to said lower drum, means for varying the amount of heat supplied by said fuel burner, an electric resistance heater in said upper drum, means for varying the amount of heat supplied by said resistance heater, means responsive to vapor pressure in said receptacle controlling both said means for varying adapted to vary both said means simultaneously.

9. Apparatus for continuously heating and vaporizing fluid at a predetermined temperature comprising a receptacle sub-divided into an upper drum and at least one lower drum connected thereto, circulatory tubing communicating with said lower drum, a fuel burner in heating relationship to said lower drum, means for varying the amount of heat supplied by said fuel burner, an electric resistance heater in said upper drum, means for varying the amount of heat supplied by said resistance heater, means responsive to vapor pressure in said receptacle controlling both said means for varying adapted to vary both said means simultaneously at a rate such that the proportionality between the heat supplied by said first mentioned heater and the heat supplied by said resistance heater is substantially constant throughout the working range.

10. Apparatus for continuously heating and vaporizing fluid at a predetermined temperature comprising a receptacle sub-divided into an upper drum and at least one lower drum connected thereto, circulatory tubing communicating with said lower drum, a fuel burner in heating relationship to said tubing, a muffle between said burner and said tubing, means for varying the amount of heat supplied by said burner, an electric resistance heater in said upper drum, means for varying the amount of heat supplied by said resistance heater, and means responsive to vapor pressure in said receptacle controlling both said means for varying adapted to vary both said means simultaneously.
